ATTORNEYS

UNITED STATES PATENT OFFICE.

HARRY FRANCIS KEELER, JR., OF LONGMONT, COLORADO.

BERRY BOX.

Application filed September 20, 1926. Serial No. 136,843.

My invention relates to improvements in boxes, particularly in berry boxes, and it consists in the combinations, constructions, and arrangements herein described and claimed.

An object of my invention is to provide a berry box which may be made of wood, cardboard, or other suitable material from one piece which is folded so as to make the complete box.

10 A further object of my invention is to provide a box in which the bottom is reinforced by supporting flaps which are struck from the single piece used in making the box.

15 A further object of my invention is to provide a box of the type described which may be quickly put together, and which requires a minimum amount of work for turning out the completed box.

20 Other objects and advantages will appear in the following specification, and the novel features of the invention will be particularly pointed out in the appended claim.

25 My invention is illustrated in the accompanying drawings, forming part of this application, in which

Figure 1 is a view of the blank from which the box is made,

30 Figure 2 is a perspective view of the box in a partially completed condition, showing the manner in which it is folded,

Figure 3 is a plan view of the completed box, and

Figure 4 is a sectional view along the line 4—4 of Figure 3.

35 In carrying out my invention, I provide a blank which is formed in one piece and is of the shape shown in Figure 1. This comprises a portion 1 which forms the bottom of the box, and a strip extending at right angles thereto which forms the sides and ends of the box. As will be seen from Figure 1, this strip is scored, as indicated in dotted lines at 2. At certain intervals, I have provided openings 3 which are in the nature of elongated slots. On one side of the strip is an L-shaped cut 4 at the center of two sections which form the sides. Between the bottom portion 1 and the laterally extending strip is an inwardly extending 45 cutaway portion 5. At 6, I have shown a scored line extending transversely of the portion 1. At the end of the scored line 6 is

a cut 7 extending to one edge of the bottom portion 1, while a similar cut 8 at the opposite end of the scored line 6 extends to the 55 cutaway portion 5. The scored lines are for the purpose of permitting the sections to bend readily along the lines, but they are not deep enough to weaken the sections.

From the foregoing description of the various parts of the device, the manner of forming the box may be readily understood. The bottom portion 1 is first bent along the line 6 at right angles to the laterally extending strip and the strip is then folded around the edge of the bottom portion in the manner indicated in Figure 2, the corners 1^a of the bottom portion 1 passing through the openings 3. The end portion 9 adjacent to the cut 7 is bent inwardly as shown in Figure 70 2, and the end 10 is brought around flush with the outside of the section 11 and is secured to it in any suitable manner, as by staples 12. The sections 13 adjacent to the L-shaped cuts 4 are then bent underneath the 75 bottom and the box is complete.

It will be noted that the bottom is supported at its four corners as well as along the edge of the scored line 6. The portions 13 are so positioned as to be substantially at 80 the central portion of the box underneath the bottom so that the central portion of the box is reinforced by these supports.

The construction described above makes a cheap and yet a strong box which can be 85 quickly made at a minimum cost.

I claim:

A box comprising a bottom portion having an integral strip extending laterally from one end thereof, said strip having a scored 90 line for folding one end thereof at right angles to the bottom and being provided with slots disposed inwardly from one edge of the strip in alignment with said scored line and arranged to receive the corners of the 95 box, said strip having L-shaped cuts extending inwardly from one edge thereof, and scored lines joining the extremities of said L-shaped cuts and the adjacent edge, the portion between the scored lines and the cuts 100 being foldable underneath the bottom of the box and constituting brace members for the bottom.
